Louis Blum, 2312 Tilbury St., Pittsburgh 17, Pa.

Filed Apr. 1, 1960, Ser. No. 59,999

Term of patent 14 years

(Cl. D13—7)

FIG. 4 -

FIG. 2.

FIG. 3.

FIG. 1 is a front perspective view of a combined mounting bracket and railing post embodying my new design;

FIG. 2 is a side elevational view of the combined mounting bracket and railing post shown in FIGURE 1;

FIG. 3 is a top plan view of the combined mounting bracket and railing post shown in FIGURE 1; and

FIG. 4 is a sectional view taken along the lines and in the direction of the arrows IV—IV of FIG. 1.

The front face of the mounting bracket in FIG. 1 has been shaded to indicate contrast.

I claim:

The ornamental design for a combined mounting bracket and railing post, as shown and described.
